UNITED STATES PATENT OFFICE

CARL H. HOFFSTETTER, OF ERIE, PENNSYLVANIA, ASSIGNOR TO ODIN STOVE MANUFACTURING COMPANY, OF ERIE, PENNSYLVANIA, A CORPORATION OF PENNSYLVANIA

DESIGN FOR A DOOR

Application filed May 21, 1930. Serial No. 35,706. Term of patent 14 years.

To all whom it may concern:

Be it known that I, CARL H. HOFFSTETTER, a citizen of the United States, residing at Erie, in the county of Erie and State of Pennsylvania, have invented a new, original, and ornamental Design for a Door, of which the following is a specification, reference being had to the accompanying drawings forming a part thereof wherein

Fig. 1 shows a front elevation of the door showing my new design.

Fig. 2 a side elevation of the door.

Fig. 3 a plan view of the door.

I claim:

The ornamental design for a door as shown.

CARL H. HOFFSTETTER.
